SERVING TRAY

George Harold Hart, Chicago, Ill., assignor to McGraw Electric Company, Elgin, Ill., a corporation of Delaware

Application December 24, 1949, Serial No. 6,827

Term of patent 14 years

(CL. D44—10)

To all whom it may concern:

Be it known that I, George Harold Hart, a citizen of the United States, residing in Chicago, county of Cook, and State of Illinois, have invented a new, original, and ornamental Design for Serving Tray, of which the following is a specification, reference being had to the accompanying drawings, forming a part thereof, in which

Fig. 2 is a perspective view;

Fig. 3 is a side elevational view, partly in section; and

Fig. 4 is an end elevational view thereof, partly in section.

I claim:

The ornamental design for a serving tray, substantially as shown.

GEORGE HAROLD HART.
